CLAIM

The ornamental design for a wall-mounted wireless power transmitter with slide-in wings, as shown and described.

DESCRIPTION

FIG. 1 is a front perspective view of a wall-mounted wireless power transmitter with slide-in wings;

FIG. 2 is a rear perspective view of a wall-mounted wireless power transmitter with slide-in wings;

FIG. 3 is top view of a wall-mounted wireless power transmitter with slide-in wings; and,

FIG. 4 is a side view of FIG. 1.

Applicants disclaim those portions of the antenna arrangement not shown in the drawings as forming no part of the claimed design. Those portions of the wireless power transmitter shown in broken lines in the drawing form no part of the claimed design.

1 Claim, 3 Drawing Sheets
